UNITED STATES PATENT OFFICE.

GUSTAV F. SIEVERN, OF PITTSBURG, PENNSYLVANIA.

CHAIN DRIVING GEAR FOR LOCOMOTIVES, STEAMBOATS, &c.

SPECIFICATION forming part of Letters Patent No. 280,091, dated June 26, 1883.

Application filed May 2, 1883. (No model.)

To all whom it may concern:

Be it known that I, GUSTAV F. SIEVERN, of Pittsburgh, in the county of Allegheny and State of Pennsylvania, have invented a new and Improved Chain Driving Gear for Locomotives, Steamboats, &c., of which the following is a full, clear, and exact description.

My invention consists of a train of carrier-pulleys intermediate to the driving-pulley, to which the power is applied, and the pulleys on the axles by which the power is transmitted, said driving, carrying, and transmitting pulleys being arranged to facilitate the application of two chain belts from one double-faced driving-pulley to both axles of a truck, so as to insure the positive and certain connection of the chains with the pulleys that is necessary for transmitting power for such purposes, the arrangement of the said driving, carrying, and transmitting pulleys being in a simple housing-frame of parallel bars and posts or uprights mounted on the axles and supporting the bed-frame of the truck or locomotive, all as hereinafter fully described.

Reference is to be had to the accompanying drawings, forming part of this specification, in which similar letters of reference indicate corresponding parts in both the figures.

Figure 1 is a longitudinal sectional elevation 30 of a truck contrived with driving-gear of my invention, the section being taken on the line $x' x'$ of Fig. 2, which is a plan view.

I provide the truck or locomotive axle a , of any form of machine or vehicle to which the power is applied, with a transmitting-pulley, b , which is connected to the axle between two uprights, c , of a pair of housing-frames, of which said uprights c form the verticals; and d represents the horizontal bars between which all the driving-gear is mounted, and in which the axles of all the pulleys, except pulleys b , have bearings, these being supported by the truck-axles, for which the truck-wheels n serve for bearings, and on which axles the housing-frames have their bearings.

The driving-pulley e is mounted in forwardly-projecting extensions d' of the housing-frames, which have brackets f suspended by hangers h from the front ends, for the connection of an extension of the bed-frame g , which is mounted on similar brackets, i , of the uprights c . Between the uprights c , I have arranged a couple of guiding or carrying pulleys, $j k$, for the chains, and above the axles,

and also above the plane of the driving-pulley e and pulleys $j k$, I have arranged two other but smaller carrying-pulleys, $l m$, in the extensions of the uprights c above the horizontal bars.

All the pulleys are double—that is to say, they have two chain-grooves side by side for the use of two endless driving-chains, x and y , which are arranged upon the pulleys as represented, but may be arranged in any approved way. The pulleys may have spurs for engaging the links of the chains to insure positive action; but they may be smooth on the face, if preferred.

It is believed that this improved arrangement of driving-gear will be preferable to other forms in respect of the percentage of useful effect obtained from the engine; also, in the facility it affords of multiplying the speed above the speed of the engine, and also in the economy of power by the diminution of the friction of the driving parts.

I also propose to utilize this improved motive-power apparatus for driving steamboat paddle-wheels and screw-propellers, to which it may be applied in various ways.

The housing-frames $c d$ are to be connected together by suitable stay rods or bars, o , whenever needed.

Having thus described my invention, what I claim as new, and desire to secure by Letters Patent, is—

1. The driving-pulley e , carrier-pulleys $j k$ and $l m$, the transmitting-pulleys b , and chains $x y$, in combination with the axles a of a truck or other vehicle or machine, substantially as described.

2. A motive-power apparatus consisting, essentially, of the driving-pulley e , carrying-pulleys $j k l m$, and transmitting-pulleys b , and chains $x y$, the said pulleys and chains arranged in the housing-frame c , d , and d' , and said frames arranged on the axles a , substantially as described.

3. A motive-power apparatus consisting of driving-pulley e , carrying-pulleys $j k$ and $l m$, and the transmitting-pulleys b , and chains $x y$, the said pulleys having double faces—that is to say, separate grooves for each chain and the chains arranged thereon as traced by the letters $x y$ —substantially as described.

Witnesses: GUSTAV F. SIEVERN.

P. MONTEVERDE,
R. W. McLAUGHLIN.
